PORTABLE ROAD ROLLER

Raymond W. Keeler, Galion, Ohio, assignor to
Galion Iron Works & Manufacturing Com-
pany, a corporation of Ohio

Application July 27, 1935, Serial No. 33,543

27 Claims. (Cl. 94—50)

My invention relates to portable road rollers and is particularly adapted for operation on patches or repair of previously built roads, but in addition to rolling patch material it may have 5 a general application for compacting loose material, rolling drives, lawns, etc.

One of the objects of the present invention is the provision of a self-contained power-operated roller which may be readily adapted to a hauling 10 vehicle, such as a truck, and the roller raised up off the ground to enable the truck to transport the road roller from place to place at truck speed.

Another object of the invention is the provision in a self-contained power-operated roller, 15 of reversing mechanism so connected to a clutch between the engine and the power transmission mechanism that whenever the reversing gearing is moved to neutral position the clutch will be released, without interfering with the normal operation of applying and releasing the clutch when the reversing gearing is in either of its 20 transmission positions.

A further object of the invention is the provision in a self-contained power-operated road roller, of a single lever movable longitudinally 25 of the machine for controlling the reversing gearing and operating the clutch.

Another object of the invention is the provision of tiltably mounting the rear axle of a road 30 roller to permit one of the rear wheels to ride along a curb while the roller operates along the gutter of a roadway.

A still further object of the invention is the provision of improved and efficient mechanism 35 for adjusting the relative positions of a vehicle unit and a roller unit, to enable the vehicle unit to be hitched to a hauling vehicle while the roller unit is lifted off the roadway for fast transporta-
tion.

40 A further object of the invention is the provision of improved and efficient fluid-pressure mechanism for adjusting a road roller unit relative to a vehicle frame.

Another object of the invention is the provision 45 in a self-contained power-operated roller, of means operable from the operator's station for flowing liquid onto the rolling surface of the roller.

A further object of the invention is the provision 50 of improved mechanism for hitching the road roller to a hauling vehicle and locking the rear steering wheels in position to travel along paths parallel to the path of travel of the machine while being transported by the hauling vehicle.

Other objects of the invention will appear hereinafter, the novel features and combinations being set forth in the appended claims.

In the accompanying drawings,

Fig. 1 is an elevational view of a self-contained power-operated road roller embodying my improvements;

Fig. 2 is an enlarged sectional elevation taken on the line 2—2 of Fig. 1, looking in the direction of the arrows;

Fig. 3 is a side elevation of the machine shown in Fig. 1 with the front hitching mechanism adjusted to such elevation as to be in readiness to be connected to a hauling vehicle;

Fig. 4 is a rear view of the machine illustrating 15 operation of the roller in a gutter while one of the rear steering wheels travels along the elevated surface of a curb;

Fig. 5 is an elevational view of the relative positions of the parts when the portable road 20 roller is hitched to a hauling vehicle and the road roller is adjusted to a position up off the road for fast transportation with the hauling vehicle;

Fig. 6 is a sectional view taken on the line 6—6 of Fig. 5, looking in the direction of the 25 arrows;

Fig. 7 is a sectional elevation of a portion of the transmission brake applying mechanism;

Fig. 8 is a sectional elevation taken on the line 8—8 of Fig. 9, looking in the direction of 30 the arrows;

Fig. 9 is a sectional elevation of the transmission;

Fig. 9a is a sectional elevational view of the 35 brake mechanism mounted in the brake drum at the right-hand end of Fig. 9;

Fig. 10 is a plan view of the machine shown in Fig. 1;

Fig. 11 is a sectional elevational view of the elongated reciprocating hydraulic motor pivot- 40 ally connected at its ends between the vehicle frame and the frame of the roller unit;

Fig. 12 is a diagrammatic view of the hydraulic connections to the hydraulic motor illustrated 45 in Fig. 11;

Fig. 13 is an elevational view of the mechanism for operating the valve shown at the middle portion of Fig. 11;

Fig. 14 is an elevational view, partly in section, 50 of the hydraulic pumping mechanism for operating the hydraulic motor shown in Fig. 11;

Fig. 15 is an elevational view, partly in section, 55 of the mechanism enabling a single actuating lever to effect reversal of the machine and the

operation of the clutch shown at the left-hand end of Fig. 9;

Fig. 16 is a sectional elevational view of a modified valve and double acting pump adapted to operate the hydraulic motor shown in Fig. 11;

Fig. 17 is an elevational view, partly in section, of the left-hand side of the double acting pump and valve shown in Fig. 16;

Fig. 18 is a sectional plan view taken on the line 18-18 of Fig. 16;

Fig. 19 is a sectional plan view taken on the line 19-19 of Fig. 17;

Fig. 20 is a sectional elevational view taken on the line 20-20 of Fig. 19;

Fig. 21 is a diagrammatic view of the hydraulic circuits and connections for enabling the double acting pump to operate the hydraulic motor illustrated in Fig. 11;

Fig. 22 is a rear end view of the machine;

Fig. 23 is a sectional elevation of the rear wheel brake actuator; and

Fig. 24 is a section taken on the line 24-24 of Fig. 22.

By referring to Figs. 1 and 22 it will be seen that the vehicle frame comprises a rearwardly extending support 22 and forwardly extending side members 23, 23, the front ends of which are connected by the cross-piece 24. The rear end of the vehicle frame is supported on the rear axle 25 to the ends of which are pivoted at 26, 26 on vertical axes the rear steering wheels 27, 27.

To the central portion of the front cross-piece 24 is adjustably connected by means of bolts 28, the vertical plate 29 which carries a hitching device 30. This hitching device may be in the form of a gooseneck having an abutment collar 31 and a conical nose 32 at its outer lower end to guide the neck 33 through an opening 34 in the horizontal plate 35 which is bolted at 36, 36 to the rear end of the truck frame 37 of a self-propelled vehicle, such as a truck, as shown in Fig. 3. By means of a series of bolts 28 and the vertical row of holes 38 in the plate 29, the latter may be adjusted in elevation through a relatively wide range because the uppermost hole 38 may be lowered to the middle bolt and the lowermost hole 38 may be elevated to the middle bolt. Consequently while the roller is in the position, as shown in Fig. 3, the hitching device 30 may be lowered sufficiently to permit the neck 33 to extend through the opening 34 in the plate 35, whereupon a cotter pin may be inserted in the opening 39 to lock the hitching device 30 to the rear end of the truck frame 37. It will thus be seen that the roller may be operated by trailing behind a self-propelled truck.

As shown in Figs. 1 and 2 a stationary transverse bearing shaft 40 is secured at its ends by means of the nuts 41, 41 to the spaced-apart side members 23 on the main or vehicle frame. Journaled on the ends of the bearing shaft 40 at 42, 42 is a transverse tube 43 to which is welded at 44, 44 the side members 45, 45 of a supplemental frame or sub-frame. The forward ends of the side members 45, 45 are connected by the cross-piece 46.

Between the side members 45 of the sub-frame 45 (Fig. 6) is secured by means of the locking discs 47, 47 and the cap screws 48, 48 the transverse stationary bearing shaft 49. On the end portions of this shaft 49 at 50, 50 is journaled the central tubular or sleeve portion 51 of the roller 52. It will thus be seen that the stationary shaft 49 acts as an axle for the drum 52 to ro-

tate upon when in contact with the ground and driven thereover.

The drum 52 is hollow, as shown in Fig. 6 which is a sectional view taken on the line 6-6 of Fig. 5 looking in the direction of the arrows. A filling opening is closed by the screw plug 53 after the hollow roller drum 52 has been filled with liquid such as water. The weight of the roller may be regulated by the amount of water placed therein, and when desired the water may be drained from the roller so as to lighten the same for transportation back of the truck, as shown in Fig. 5.

Intermediate the ends of the front cross-piece 46 of the sub-frame are mounted the upright supports 54, 54 which may be welded at their lower ends to the cross-piece 46 so as to occupy the position illustrated in Fig. 10. Between the upper ends of the supports 54, 54 is secured the transverse bearing rod or pin 55 to which is pivoted or journaled the upper end of the piston rod 56, to the lower end of which is secured a piston 57 movable up and down in the hydraulic cylinder 58, as shown in Fig. 11.

The lower end of the cylinder 58 is secured to a block 59 pivoted at 60 to the brackets 61, 61 which extend rearwardly from the central portion of the front cross-piece 24 of the main frame, as shown in Fig. 10. The piston rod 56 extends upwardly out of the cylinder 58 through the stuffing box 62, as shown in Fig. 11. The hydraulic structure shown in Fig. 11 constitutes an elongated reciprocating hydraulic motor between the ends of the vehicle frame and the supplemental frame, for adjusting the relative positions of the front ends of these frames, as illustrated in Figs. 1, 3 and 5 and more fully hereinafter explained.

As shown in Fig. 6, a supporting ring 63 is secured, preferably by welding, to one of the end plates 52' of the roller 52 and to this ring 63 is secured by means of the cap screws 64, the ring sprocket 65 with which is adapted to mesh the endless sprocket chain 66 which also meshes with the driving sprocket 67 of the power transmission mechanism shown in Fig. 9.

Secured to one of the side members 45 of the supplemental frame so as to be rigid with the latter is a rearwardly extending protecting cover 68 for the sprocket 67. In fact the protecting cover 68 may if desired be secured to the rear end of the casing 69 and the latter secured to the sub-frame 45 by means of the cap screws 70, as shown in Fig. 5. The casing 69 extends over the entire upper portion of the roller 52 by fitting over not only the side members 45 but also the front cross-piece 46 and having its upper side closed to provide a receptacle for patching tools at 71 (Fig. 10) and in one corner of the latter a small tool box 72. At the rear portion of the casing 69 is an enclosed water compartment 73 normally closed by the cover 74. From the bottom of the water tank 73 at 75, the water may pass to the transverse sprinkler pipe 76 which is located adjacent the roller 52, as shown in Figs. 1 and 10. By means of a pull and push rod 77, a lever 78 (Fig. 10) may be actuated to open or close the valve 79 which controls the passage of the water from the water tank 73 to the transverse sprinkler pipe 76. The cover plate 74 may be provided with filling openings which are normally closed by the filler caps 80, 80, as shown in Fig. 10. Whenever during operation of the roller the latter has a tendency to pick up material, the valve 79 may be opened

so as to flow water over the entire width of the operating face of the roller, thereby loosening adhering material and preventing the picking up of additional material from the roadway.

5 Secured to the rear ends of the side members 45 of the sub-frame, preferably by means of welding, is a bed plate 81 which is adapted to support the internal combustion engine and the power transmission mechanism between the same and the roller propelling endless sprocket chain 66. The bed plate 81 also constitutes the rear cross-piece of the sub-frame having the side members 45, 45. A plurality of bolt openings are distributed along the bed plate 81 at 82, 83, and 84 (Fig. 2) to enable the internal combustion engine and the power transmission mechanism to be very securely connected to the sub-frame. The internal combustion engine 85 may be provided with a starting crank 86 at one end thereof, as shown in Fig. 10. This internal combustion engine may comprise four cylinders equipped with an air cleaner, magneto with impulse starter, governor and fan. The engine is preferably entirely enclosed and so also the power transmission gearing which operates on friction reducing bearings in an oil bath (Fig. 9).

At that end of the internal combustion engine 85 remote from the starting crank 86 is a fly wheel 87 with which is associated the clutch 88 for connecting the engine to the plural speed power transmission mechanism shown in Fig. 9, under the control of the operating lever 89 which is located within convenient reach of the operator while sitting on the seat 90 or standing on the platform 91 at the rear end of the machine.

When the clutch 88 is applied, power will be transmitted from the internal combustion engine to the transverse shaft 92, as shown in Fig. 9. The shaft 92 extends through the stuffing box 93 and is journaled by means of the ball bearings 94 to the supporting partition 95 which may be integral with a part of the enclosing casing 96. At the right-hand end of the shaft 92 is a pinion 97 which meshes with an internal annular gear 98, the hub 99 of which is keyed to the sleeve shaft 100 which in turn is journaled by means of the roller bearings 101, 101' on the stationary bearing shaft 102. The ends of the stationary bearing shaft 102 are mounted in the partitions 95 and 103.

The sleeve shaft 100 carries spaced-apart pinions 104 and 105 which mesh respectively with the gear 106 and the idler 107, as shown in Figs. 8 and 9. The idler 107 meshes with the gear 108.

The gears 106 and 108 are journaled by means of the roller bearings 109 and 110 on the reversing shaft 111, the left-hand end of which is journaled in the casing 112 by means of the ball bearings 113. The left-hand end of the sprocket shaft 114 is reduced in diameter and journaled by means of the roller bearings 115 in the cylindrical recess at the right-hand end of the reversing shaft 111. The right-hand end portion of the shaft 111 is journaled by means of the ball bearings 116 in the casing 112.

The opposing inner faces of the gear elements 106 and 108 are provided with internal annular gears 117 and 118 with which are adapted to mesh the gears 119 and 120 on the shiftable clutch element 121. A shipper 122 is adapted to slide the clutch element 121 along the splines 123 on the shaft 111. It will thus be seen that while the clutch element 121 together with its gears 119 and 120 are mounted to slide along the

shaft 111, they always rotate with the latter; whereas the gear elements 106 and 108 are mounted loosely on the shaft 111 and do not rotate therewith unless the gear 119 meshes with the gear 117 or the gear 120 meshes with the gear 118. When the gear 119 meshes with the gear 117, motion will be transmitted from the engine to the clutch 88, the shaft 92, gears 97, 98, and gears 104, 106, in one direction, whereas opposite direction of rotation of the shaft 111 will be secured when the gear 120 meshes with the gear 118, because in such event the transmission will be through the gears 105, 107 and 108, as shown in Figs. 8 and 9.

Mounted on the right-hand end of the shaft 111 is a pinion 124 which meshes with a gear 125 mounted on the sleeve 126, the latter being in turn journaled by means of the roller bearings 127, 128 on the stationary bearing shaft 129. The right-hand end of the sleeve 126 carries a gear 130 which is of appreciably smaller diameter than the gear 125.

The sprocket shaft 114 is journaled by means of the ball bearings 131 in the supporting casing and in the cap 132 which is secured by means of cap screws one of which is shown at 133 at the right-hand portion of Fig. 9.

The sprocket shaft 114 is splined at 134 intermediate its ends to carry the speed shifting gear element 135. This speed shifting element is provided with a gear 136 which is adapted to mesh with the gear 130 when the element 135 is shifted toward the right, as viewed in Fig. 9. The left face of the element 135 carries an internal annular gear 137 which is adapted to mesh with the pinion 124.

A gear shift lever 138 may be mounted on the support 139 as shown in Fig. 9 for connection at its lower end with the gear shift element 135. The rod 140 may be notched at 141 to receive the spring pressed latch 142, and connected to the lower portion of the gear shift lever 138 to enable the operator to determine to what positions to move the lever when the speed of transmission is to be varied. After the gears 137 and 124 have been brought into mesh, the gear shift lever 138 may be locked by movement into the notch 143, and when the gears 136 and 130 have been brought into mesh, the gear shift lever 138 may be locked by movement into the notch 144. It can readily be seen by referring to Fig. 9, that when the gears 137 and 124 are in mesh, fast speed will be transmitted to the sprocket 67 and thence to the road roller, but if the gears 130 and 136 are brought into mesh a slower speed will be transmitted. Inasmuch as the reversing gear mechanism determines the direction of movement of the machine, the arrangement shown in Fig. 9 provides for two speeds forward and two speeds in reverse.

Inasmuch as the brake drum 145 is keyed to the sprocket shaft 114 it will rotate therewith. The brake mechanism 145 which is associated with the rotating brake drum 145' is preferably of the expansion type and so connected to stationary supports mounted on the bed plate 81 as to enable the brake lever 146 to be moved longitudinally of the machine from the operator's station at the rear end of the machine. The double arm cam 147 shown in Fig. 9a may be directly actuated by the brake lever 146 connected to the rock shaft 148. By means of the pawl and ratchet mechanism shown at 149 in Fig. 7, the brake mechanism 145 may be held partially applied for retarding the machine when operating.

on steep grades. This will enable a single operator to control the machine on steep grades by using one hand for the steering wheel and the other hand for operating the reverse gearing which is so arranged, as shown in Fig. 15, that whenever the reversing gear element 121 is in neutral position, the clutch is released. However, since the brake may be applied when the clutch is released, the machine will not get out of control on steep grades. As shown in Fig. 9, a protective covering 150 secured to the stationary ring 132 may be provided for the brake mechanism 145 within the brake drum 145'.

As shown in Fig. 15, the lever 89 for operating the reversing mechanism is keyed to the hub of a bevel gear 151 which is journaled on a stub shaft 152 secured rigidly to the bracket 153 which extends rearwardly from the casing 96. The bevel gear 151 meshes with another bevel gear 151' which is mounted to rotate on a stationary longitudinal axis 154, and is secured to a short horizontal V-shaped actuating lever 155 and to a relatively long actuating lever 156 which extends downwardly and is connected at its lower end by the link 157 to the short lever arm 158 keyed to the rock shaft 159. It should be understood that the link 157 is pivoted at 160 at its upper end to the lower end of the arm 156, and that the lower end of the link 157 is pivoted to the outer end of the arm 158. The rock shaft 159 carries the shipper 162 shown in Fig. 9. It can readily be seen by referring to Fig. 15 that whenever the lever 89 is moved forwardly or rearwardly the arm 156 will be swung transversely of the machine or longitudinally of the transversely mounted power transmission mechanism shown in Fig. 9. Whether the actuating arm 156 is swung in one direction or the other, the outer end of the lever arm 158 will be lifted and consequently the rock shaft 159 will be moved in an anti-clockwise direction which will cause the upper ends of the shipper 162, shown in Fig. 9, to be moved toward the left to effect application of the clutch 88.

This clutch may be of well known construction comprising a ring 163 secured to the fly wheel 87 to rotate therewith. The clutch disc 164 is mounted on the hub 165 which in turn is splined to the left-hand end of the shaft 92. Screw-threaded into the ring 163 is an abutment ring 166 against the inner face of which are adapted to engage the cams 167. A floating ring 168 is connected by springs 169 to the ring 163. Levers 170 are fulcrumed adjacent the cams 167 in U-shaped supports 171 projecting from the floating ring 168. When the upper ends of the shipper 162 move toward the left, as viewed in Fig. 9, the cams 167 will force the rings 168 and 163 apart against the action of the springs 169 and thus effect application of the clutch through the friction rings 172. Limit stops are provided at 173 to obtain the proper limiting positions of the cams 167.

The ball bearing cage 174 is connected to the upper ends of the shipper arms 162 and this ball bearing cage is connected by means of the ball bearings 175 to the clutch actuating mechanism. It will thus be seen that when the clutch has been applied the rings 168 and 163 may rotate together with the parts connected thereto and thus transmit motion to the shaft 92 while the ball bearing cage 174 is held by the shipper 162 against rotation.

Referring again to Fig. 15, it will be seen that the short V-shaped lever arm 155 projecting 76 toward the right from the bevel gear 153, engages

a Y-shaped device 176 which is rigidly connected to the depending actuating arm 177 and pivotally mounted on the bearing 178. To the lower end of the lever arm 177, is pivoted at 179 the left-hand end of a slide rod 180 which is mounted to slide in the bearings 181 and 182. By means of spring-pressed ball latch mechanism 183, the slide rod 180 will be held in any one of three positions to which it has been moved. Intermediate the ends of the slide rod 180, is pivoted the lever arm 122' of the shipper 122 shown in Fig. 9. It should be understood that when the lever 89 is moved in one direction the reverse gearing will be operated to effect a certain direction of movement of the machine, and when the lever 89 is moved in the opposite direction the reverse gearing will be operated to move the machine in the opposite direction. For instance, if the reverse gear element 121 shown in Fig. 9 is moved toward the left the machine may be moved forward, and when the reverse gear element 121 is moved toward the right, the machine may be moved rearwardly. When the reverse gear element 121 is in its neutral position as shown in Fig. 9, the slide rod 180 will occupy the position shown in Fig. 15 and the connections to the clutch at the left-hand end of Fig. 9 will be such as to release the same. It should be particularly noted that whenever the reverse gear mechanism shown in Fig. 9 is in neutral position, the clutch will always be released.

However, when the reverse gear element 121 is in transmitting position either at the left or at the right, as viewed in Fig. 9, the Y-device 176 shown in Fig. 15, will occupy such a position as not to interfere with the application and release of the clutch shown at the left-hand end of Fig. 9. In other words, the machine may be started and stopped whenever desired while going in the same direction but when reverse movement of the machine is to be effected the clutch will be compelled to be moved to released position by reason of the interlocking connection shown in Fig. 15, when the gear shifting element is moving through its neutral position. When the machine is to be reversed on steep grades, the brake 145, 145' may be applied and held applied to any extent desired, as above described.

When the operator is at his station at the rear end of the machine he may with one hand operate the steering wheel 184 while with the other hand he may move the reversing lever 89 either forwardly or rearwardly while the brake 145, 145' is set partially applied, as indicated by the latch mechanism 149 in Fig. 7. In this manner a single operator may readily control the operation of the roller back and forth on a steep grade either uphill or downhill.

The forward and reverse motion of the roller is therefore controlled by a single conveniently located lever at the operator's station at the rear end of the machine. The gear shift lever and the hand brake lever, the motor ignition and the control rod 71 for the sprinkler valve 79, are also within easy reach of the operator at the single station at the rear end of the machine. The steering wheel 184 may be of the large automotive type and connected by means of the gearing 186 to the depending lever arm 187 and thence by the link 188 to the U-shaped crank 189 which is connected directly to one wheel and by means of the link 190 which is connected to the crank 191 to the other wheel, as shown in Fig. 10. The steering of the machine is effected by turning the

wheels 27, 27 on the vertical axes 26, 26 relatively to the rear axle 25.

When the roller is operated as a self-propelled road roller, the main and supplemental frames 5 are arranged as shown in Fig. 1, the front ends of the frames being locked in adjusted positions relative to each other by the hydraulic motor 58 having its piston locked against movement in either direction. The side members 23 of the 10 main frame have attached thereto inwardly extending abutment blocks 192 which abut against blocks 193 extending from the sides of the side members 45 of the sub-frame, as shown in Figs. 5 and 10.

15 In some instances it may be desired to operate the roller by being towed back of a self-propelled truck. For instance, if the driving chain 66 is disconnected and the upper end of the piston rod 56 is disconnected from the upper ends of the 20 supports 54, the roller construction shown could be operated as a trailer road roller. After disconnecting the upper end of the plunger 56 from the supports 54, the elongated hydraulic motor cylinder 58 could be leaned forward and held there 25 or disconnected at 60 from the bracket 61. While being towed by a self-propelled truck, an operator could be stationed at the rear end of the machine to actuate the steering mechanism. In the event that this operation is effected, the front end of the 30 vehicle frame would be held at adjusted elevation by the supporting plate 35 at the rear end of the truck frame 31, the rear end of the vehicle frame would be supported on the steering wheels 27 and the roller itself would be free to 35 move up and down on its pivot 40 relatively to the vehicle frame, between the side members 23 thereof.

When operating the roller as a trailer road roller while connected to a towing self-propelled truck, the services of an operator for the steering wheel 184 could be dispensed with by locking the steering wheels 27 in position to follow the path of travel parallel to the path of travel of the truck wheels 194.

45 By referring to Figs. 4 and 10 it will be seen that the cross-piece 23' which connects the rear ends of the side members 23 of the vehicle frame is provided with a relatively narrow rearwardly extending frame 22. Pivoted to the frame 22 at 195, as shown in Fig. 1, is a latch plate 196 which may be moved downwardly by means of a rearwardly extending pull rod 197 which is pivoted at its forward end at 198 to the upper end of the latch plate 196. This latch plate 196 is located midway between the sides of the frame 22, as shown in Fig. 10. The cross-link 190 of the steering mechanism has welded thereto, two rearwardly extending spaced-apart plates 199, 199 to provide a slot between the same for receiving the latch plate 196. Consequently, when the 50 wheels 27 are symmetrically arranged, as shown in Fig. 10, the latch plate 196 may be inserted in the slot between the plates 199 and thus lock the steering mechanism against being operated. The locking position of the latch plate 196 is illustrated in Fig. 5. The locking of the rear steering wheels against movement in either direction on their vertical axes 26 is also useful when the roller is elevated off the roadway, as shown in Fig. 5, 55 and being towed at transportation speed back of a self-propelled truck.

As shown in Fig. 10, diagonal brace rods 200, 200 are secured at their rear ends to the axle 25 near their outer ends. The forward ends 70 of the brace rods 200 are connected to a support

201 which is pivoted on a longitudinal axis 202 to the frame 22 midway between the sides thereof. The longitudinal pivot 22 is in alignment with the rear pivot shown at 203 in Fig. 4. It will thus be seen that the axle frame structure comprising the axle proper 25 and the diagonal rods 200 are pivoted to the frame 22 at spaced-apart points 202 and 203 which are in longitudinal alignment with each other.

The rear axle 25 is pivoted at 203 to the spaced parallel transverse plates 22' depending from the rear end of the frame 22, as shown in dotted lines in Fig. 1. The axle 25 carries an inverted V-shaped plate 204 at the center thereof, as shown in Fig. 4. This plate is perforated at its upper end at 205 and this perforation may be brought into registry with the perforations 206 in the rear spaced-apart transverse parallel plates 22' as shown in dotted lines in Fig. 1. A locking pin 207 may be inserted through the registering 10 openings 205 and 206 to lock the rear axle against tilting movement on the longitudinal axis 203. The locking pin 207 at its rear end is provided with a perforation 208 (Fig. 10) adapted to be brought into registry with the perforation 209 in a horizontally extending bracket plate 209, and another locking pin may be inserted through these perforations so as to lock the locking pin 207 in place. This locking is desired when the machine is operating over level roadways or when it is being towed over level roadways. When the roller is operating in a gutter with one wheel 27 traveling along the curb, as shown in Fig. 4, the plate 204 remains unlocked and the locking pin 207 may then be inserted in the opening 210 and 15 held in position by the pin 211 for safe-keeping.

20 Referring now to Figs. 12, 13 and 14, I will describe the hydraulic control system for the elongated hydraulic motor pivotally connected at its ends between the main and supplemental 25 frames. The manually operated pump 212 shown in Figs. 13 and 14 may be mounted on the cross-piece 24 at the forward end of the main or vehicle frame, as shown in Fig. 10, so as to be in proximity to the elongated hydraulic motor illustrated in Fig. 11. A lever 213 is connected to 30 valve mechanism to control the direction of flow to and from the cylinder 58 of the hydraulic motor shown in Fig. 11. The pressure medium is preferably oil which is placed in the casing 214, 35 the latter serving as the liquid reservoir or source of supply of the pressure medium. This reservoir may comprise a base 215 and a cap plate 216 connected by the cylinder 217 and bolted together as illustrated at 218, 218. The lever 213 is connected to the upper end of a rod 219 which extends downwardly through the stuffing box 220 and through a stationary bearing block 221 at the lower portion of the reservoir 214.

To the lower end of the rod 219 is connected 40 a pinion 222 which meshes with two separate gears 223 and 224 mounted on vertical valve stems, the upper ends 225, 226 of which slide vertically in bearings in the stationary bearing block 221.

45 The vertical valve stems are screw-threaded at 227, 228 below the gears 223 and 224 and fit screw-threaded openings in the central portion of the base 215. Below the screw-threaded portions 227, 228 the valve stems are reduced in 50 diameter to afford free passageway around the same for oil from the reservoir 214 through the vertical openings 229, 230 which extend from the upper centers of the valve stems to a lateral 55 passageway communicating with the recesses 70 75

229', 230' in the base 215, as shown in Fig. 13. At the lower ends of the valve stems are valves 231, 232 which are adapted to be seated when moved downward sufficiently to engage the base block 215. When the valve 231 is open as shown in the left-hand portion of Fig. 13, communication will be established between the chamber 229' and the passageway 233. When the valve 232 is closed, as shown in the right-hand portion 10 of Fig. 13, the communication between the chamber 230' and the passageway 234 is closed. It should be understood that the screw-threads 227 and 228 are respectively right-handed and left-handed, and therefore when the pinion 222 rotates the gears 223, 224, one valve 231 will be moved up while the other valve 232 will be moved down, and vice versa. It is the opening and closing of the valves 231, 232 by means of the lever 213 that controls the direction which the 15 piston 57 will take when the manually operated pumping mechanism shown in elevation in Fig. 14 is operated.

The manually operated pumping mechanism shown in elevation in Fig. 14 comprises an actuating lever 235 pivoted at 236 to give the arms 237, 237' an oscillating movement and thereby move one piston plunger 238 up while moving the other down. Each of the cylinders 239, 239' has at the lower end thereof check valves—the one 20 designated 240 opening upwardly, and the other designated 241 opening downwardly. Liquid may flow into the cylinder 239 at the port 242 past the check valve 240 and the liquid may flow from the cylinder 239 past the check valve 241 out from the port 243.

The operation may best be understood by reference to Fig. 12. When the valve 232 is closed and the valve 231 is open and the piston 238' is moving downwardly, liquid from the cylinder 40 239' may move past the check valve 241' through the pipes 244, 245 into the chamber 229' and thence through the vertical opening 229 into the liquid reservoir. This exerts no operating pressure through the pipe 246 into the cylinder 58 above the piston 57. When the piston 238' moves down, the piston 238 moves up but the upward movement of the piston 238 opens the valve 240, drawing liquid into the cylinder 239 from the reservoir through the pipe 247. Upward movement of the piston 238 closes the valve 241. Consequently, downward movement of the piston 238' and upward movement of the piston 238 while the valve 232 is closed and the valve 231 is open, permits the piston 57 to remain in its 45 position shown in Fig. 12, but the cylinder 239 has been filled with liquid in preparation for an operation of the hydraulic motor 58.

Upon downward movement of the piston 238 from its position shown in Fig. 12, the valve 240 60 will be closed but the valve 241 will be opened and the liquid will be forced through the pipe 248 into the cylinder 58, thereby forcing upwardly the piston 57. When the piston 57 moves upwardly the liquid above the same is free to move through the pipe 246 into the pipe 245 and thence through the chamber 229' and the passageway 229 into the supply reservoir 214. The upward movement 65 of the piston 238' will automatically open the valve 240' and close the valve 241'. The upward movement of the piston 238' therefore draws in a supply of liquid into the cylinder 239'.

After the piston rod 56 has been moved upwardly to the desired extent to lift the front end of the sub-frame to an elevated position relative 70 to the vehicle frame, as illustrated in Fig. 5,

the roller will be raised off the roadway and the weight of the structure will be exerted downwardly on the piston 57 of Fig. 11. The valve 232 being closed and the check valve 241 having automatically closed, there will be no tendency 15 for the roller sub-frame to move out of its adjusted position even after the actuation of the manual pumping mechanism is discontinued.

After the road roller has been towed to its destination as illustrated in Fig. 5, it may be let 10 down to the road surface by simply opening the valve 232 and closing the valve 231. The weight of the front end of the roller unit will then exert downward pressure on the piston 57 and the liquid below the same will flow through the pipes 248, 15 249 into the chamber 230' and thence through the passageway 230 into the supply reservoir.

After the roller 52 has engaged the road surface and it is desired to speedily unhook the tongue 30 from the rear end of the truck, the 20 manually operated pump may be actuated while the valve 231 is closed and the valve 232 is open. When the piston 238' is in its uppermost position and the cylinder 239' filled with liquid, downward movement of the piston 238' will close the check 25 valve 240', open the check valve 241' and force the liquid through the pipes 244, 246 into the cylinder 58 above the piston 57, the valve 231 being closed. The liquid below the piston 57 will then flow through the pipes 248, 249 into the 30 chamber 230' and through the passageway 230 into the supply reservoir, the check valve 241 being at this time closed. In this manner the front end of the vehicle frame may be lifted relatively to the sub-frame and therefore the tongue 30 may 35 be disconnected from the rear end of the truck 37 after which the sub-frame as shown in Fig. 3 may again be nested in the main frame, as illustrated in Fig. 1, for operation of the roller as a self-contained power-operated machine. 40

When the roller contacts with the roadway, as shown in Fig. 1, operation of the elongated reciprocating motor will lift or lower the hitching device 30. When the roller is in the elevated position shown in Fig. 5, it must first be let down 45 to the roadway before the hitching device 30 can be released by removing the cotter pin 39 and operating the hydraulic motor 58 to elevate the hook from the plate 35 to the position shown in Fig. 3.

When the sub-frame 45 is moved to the position shown in Fig. 5 for holding the roller 52 up off the roadway while being towed by the truck at transportation speed, the sub-frame may be locked in adjusted position by means of the pin 55 250 which is connected to a chain 251 and the latter secured to one of the side frame members 23. The pin 250 extends through an opening in the side member 23 and also through a registering opening in the side frame member 45. Such pins 60 250 may be used on opposite sides of the machine, as shown in Fig. 10. When the road roller is operating as a self-propelled machine as illustrated in Fig. 1, the pin 250 may be inserted 65 through registering openings in the side frame members 23 and 45 to hold the frames against relative up and down movements. After the locking pin 250 has been inserted into the registering openings, either as shown in Fig. 1 or as shown in Fig. 5, a locking plate 252 may be secured at 70 253 to the side frame members 23 to prevent the pin 250 from being vibrated out of its locking position. The locking mechanism comprising the pins 250 on opposite sides of the machine as shown in Fig. 10, secures the frames 75

together in adjusted relative positions so as to be independent of the hydraulic mechanism illustrated in Figs. 11 to 14 inclusive. In other words, the hydraulic mechanism is relied on to positively adjust the relative positions of the frames and may be relied on to hold them in relative adjusted positions, but it is preferred to add the positive locking mechanism comprising the locking pins 250, particularly when the machine is to be called upon for heavy duty over rough roadways.

Figs. 16 to 21 inclusive, illustrate the double acting pump and hydraulic connections between the same and the hydraulic motor shown in Fig. 11 so that the roller may be lifted off the roadway in less time than is possible with the single acting pump shown in Figs. 12, 13 and 14. The apparatus shown in Figs. 16 to 21, inclusive, is described and claimed in my co-pending divisional application, Serial No. 257,814, filed Feb. 23, 1939, for an improvement in a Road roller and hydraulic system therefor.

It can readily be seen by comparing Fig. 16 with Fig. 13 that the gearing and valve mechanism of Fig. 13 have been omitted and a much simpler valve structure substituted therefor at the lower end of the actuating rod 219'. In Fig. 16 the base 215' is clamped to the cap 216' by means of the cylinder 217' and the bolt rods 218'. The lever 213' is connected to the upper end of the valve rod 219'.

The valve 254 at the lower end of the valve rod 219' is slightly tapered and is pressed upwardly by the spring 255 seated in the screw cap 256 at the center of the bottom of the base 215', as shown in Fig. 16.

Fig. 18 is a sectional plan view on the line 18-18 of Fig. 16 and shows that the various passageways desired may be obtained by simple straight line boring in the base 215' and the ends of the bores closed by means of screw plugs as illustrated at 257, 258, 259 and 260.

The valve 254 is a simple two-way valve, as illustrated in Figs. 18 and 21. An opening from the reservoir 214' leads downwardly through the passageway 261 into the transverse passageway 262 to the valve 254, shown in closed position in Fig. 18. When the valve 254 is in the position shown in Fig. 21, however, weight on the piston 57 will cause the liquid to move through the pipe 248 past the valve 254 and thence through the passageways 262 and 261 into the reservoir 214'. At the same time liquid can be drawn from the reservoir through the pipe 263 past the check valve 264, pipe 265, cylinder 266, past the check valve 267, the pipe 268, pipe 269, past the valve 254, and pipe 246. In other words, this circuit will be established from the reservoir 214' to the upper portion of the cylinder 58 by suction from above the piston 57, while pressure is exerted below the latter by the weight of the piston rod 56, to force liquid into the reservoir 214'.

However, if the roller is on the roadway and it is desired to positively lift the front end of the vehicle frame to elevate the hitching device 30 preparatory to hooking it to the hauling truck, the double acting pump shown in Figs. 17 and 21 may be operated to force liquid into the cylinder 58 above the piston 57. When the piston 270 is forced down by the lever 235' the check valve 264 will be closed but the check valve 267 will be opened and liquid will therefore be forced through the pipes 268, 269 and 246 to the cylinder 58 above the piston 57. When the plunger 270 is moved down, the plunger 270' moving up will

close the check valve 271 and open the check valve 272 to draw liquid from the reservoir 214' through the pipe 273 in the cylinder 274. After the cylinder 274 has been filled with liquid and the plunger 270' is at the upper limit of its stroke, the reversal of the latter will close the check valve 272 and open the check valve 271. At the same time the upward movement of the plunger 270 will close the check valve 267 and open the check valve 264. The downward movement of the plunger 270' will force the liquid through the pipes 275, 269 and 246 into the cylinder 58 above the piston 57. It will thus be seen that upon each downward stroke of the plungers 270 and 270', liquid will be forced into the cylinder 58 above the piston 57.

By changing the position of the valve 254 from that shown in Fig. 21 to a position 90 degrees therefrom, the pipe 269 will be connected to the pipe 248 and the pipe 246 will be connected to the return passageway 262. Then upon operation of the manually operated pump, each downward stroke of the plungers 270 and 270' will force liquid into the lower end of the cylinder 58 below the piston 57, while the liquid above it will be discharged back into the reservoir. Movement of the valve 254 to the position shown in Fig. 18 will lock the piston 57 in adjusted position in the cylinder 58 and therefore hold the main and supplemental frames in adjusted relation to each other.

While the engine is operating but with the clutch 88 shown at the left hand end of Fig. 9 released, the brake mechanism shown in Figs. 9 and 9a may be applied to hold the roller stationary on the roadway. This enables the machine to be held stationary on a grade while the operator is absent from his station. It is preferred to use the brake mechanism operated by the lever 138 only for emergencies and to rely during normal operation of the machine even on steep grades, on brake mechanism associated with the steering wheels and operated by a foot pedal 277 at the operator's station.

Fig. 22 is the rear end of the machine showing the hydraulic connections between the foot pedal 277 and the brake mechanism associated with the rear wheels. Fig. 24 is a section taken on the line 24-24 of Fig. 22 looking in the direction of the arrows. Fig. 23 is a longitudinal sectional elevation of the hydraulic brake actuating mechanism connected to the foot pedals 277 for operation thereby. The hydraulic actuating mechanism shown in Fig. 23 may be mounted on one of the vertical side plates of the frame 22, as shown in Figs. 22 and 23.

The foot pedal lever 277 is pivoted to the frame 22 at 278 and is provided with a short arm 279 connected at its lower end to a spring 280, the other end of which is connected at 281 to the frame 22. Pivoted at 282 with the arm 279 is a piston rod 283, the inner end of which extends into a conical recess 284 of a piston 285 which slides along the cylinder 286 beneath an oil reservoir 287. A filler and feeder is located at 288.

When the foot is released from the pedal 277, the piston 285 occupies the position shown in Fig. 23. Reserve liquid from the tank 287 may then pass through the port 289 into the recessed area 290 surrounding the piston 285 intermediate its ends. At the right-hand end of the piston 285 is a primary cup 291. A secondary cup is located at 292 being held in place by the retaining ring 293 so as to prevent oil from leaking into the bellows boot 294.

A by-pass port is located at 295. It will thus be seen that liquid is on both sides of the primary cup 291. A double check valve is located at 296. A spring 297 extends between the primary cup 291 and the check valve 298 and an inner spring 299 associated with the check valve 300.

The pipe fitting at 301 is connected by means of the flexible hose 302, 303, 303 to the cylinder 304 of each of the brake devices shown in section in

Fig. 24. Pistons extend into opposite ends of the cylinder 304 with a spreading spring 305 between the same. The outer ends of the pistons are pivotally connected to the brake shoes 306, 306 which are adapted to engage the brake drum 307. It should be understood that the brake shoes are mounted on the non-rotatable hub portions of the wheels, whereas the brake drums 307, 307 are connected to the wheels to rotate therewith.

As soon as the operator places his foot on the pedal 277 to operate the brakes associated with the rear steering wheels, the primary cup 291 is moved toward the right and the port 295 immediately closed. Thereupon pressure will be produced in the cylinder 286 to the right of the cup 291, as viewed in Fig. 23, and the check valve 300 will open and the liquid will flow through the pipes 303 to the brake actuating cylinders 304 thereby causing application of the brake shoes to the brake drum 307 against the action of the restoring springs 305 and 308.

When the operator releases his foot the spring 280 will restore the piston 285 to its initial position shown in Fig. 23, whereupon the port 295 will be uncovered and as the brake shoes are released the liquid will flow into the cylinder 286 by opening the check valve 298 while the check valve 300 remains closed. Any excess of liquid is by-passed through the port 295 into the reservoir 287.

The brake mechanism shown in Fig. 24 and the actuating mechanism in Fig. 23 are of well known construction. Hydraulic mechanism of this or similar type is preferred because it is well adapted for mounting on the frame 22 for connection by flexible hose 303 to the rear steering wheels. In other words, the use of foot operated hydraulic brake mechanism for rear wheels enables the operator to operate the steering mechanism with one of his hands and the rear wheel brake mechanism with one of his feet without any interference. That is to say, by reason of the flexible connections at 303 the steering wheel unit may be operated without interfering with the application of the brake mechanism by the operator at will.

It should be particularly noted that when the operator releases the foot pedal 277 the brake mechanism associated with the rear wheels will be automatically released, whereas the brake mechanism associated with the right-hand end of the power transmission mechanism, as shown in Fig. 9, may be set in predetermined applied position as shown in Fig. 7, so that the roller may be held stationary on a steep grade or elsewhere during absence of the operator from the machine.

When the machine is operating with its parts related as shown in Fig. 1, it is preferred to release the brake mechanism associated with the power transmission and rely on the brake mechanism associated with the rear wheels for assisting the operator in controlling the machine. Only during emergencies or during the absence of the operator or while the machine is being towed, need the brake mechanism be applied as shown

in Fig. 7 to hold the roller against rotation relative to the frame on which it is mounted.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a road roller, the combination with a vehicle frame, of steering mechanism comprising rear supporting wheels for said frame, mechanism at the forward end of said frame for connecting the same to towing means, a supplemental frame pivoted at one end to said vehicle frame intermediate the ends of the latter, a roller carried by said supplemental frame, power-operated apparatus for driving said roller when engaging the roadway to propel said vehicle when disconnected from said towing means, said wheels and said rollers serving as the sole support for said frames when the vehicle frame is disconnected from the towing means and mechanism connected between said frames for lifting the roller up off the roadway when said vehicle frame is connected to and supported by said towing means.

2. In a road roller, the combination with a vehicle frame, of a road roller mounted thereon, a rear transverse axle pivoted to said frame on a longitudinal axis, and steering mechanism comprising rear wheels at the ends of said axle to permit operation of the roller in a gutter while one of said wheels travels in an elevated position along a curb.

3. In a road roller, the combination with a vehicle frame, of a road roller connected thereto, a rear axle pivoted to said frame to tilt relatively thereto on a longitudinal axis, mechanism for locking the axle in adjusted position relative to said frame, steering mechanism comprising rear wheels at the ends of said axle, and self-contained power-operated apparatus under control of an operator riding on the machine for propelling the latter along a surface to be rolled while one of said wheels adjacent one side of the path of the roller travels in an elevated position relative to such surface.

4. In a road roller, the combination with a vehicle frame, of supporting means at the rear end of said frame for travel along a roadway, mechanism at the front end of said frame to support the same on the rear end of a self-propelled truck frame to trail back of the same, a supplemental frame pivotally connected to said vehicle frame intermediate the ends of the latter, a roller mounted on said supplemental frame for rotation on an axis spaced horizontally in advance of the pivot between said supplemental frame and said vehicle frame, and a fluid-pressure motor for tilting said supplemental frame relatively to said vehicle frame to lift the roller up off the roadway for transportation while such vehicle frame is connected to said truck frame.

5. In a road roller, the combination with a vehicle frame, of ground engaging steering wheels for supporting the rear end thereof, mechanism at the front end of said frame to hitch the same to a hauling vehicle for transportation, a supplemental frame connected to said vehicle frame for adjustment relative thereto, a roller mounted on said supplemental frame, mechanism between said

frames for lifting the roller up off the roadway when the front end of said vehicle frame is hitched to and supported by a hauling vehicle and while said steering wheels remain in engagement with the ground, and means for locking the supplemental frame to said vehicle frame to hold the roller at adjusted elevation independently of said lifting mechanism.

6. In a road roller, the combination with a vehicle frame, of wheels always in engagement with the ground for supporting the rear end of said frame, a hollow roller adapted to be filled with liquid to increase its weight for operation, a supplemental frame pivoted to said vehicle frame and carrying said roller, mechanism at the front end of said vehicle frame to hitch the same to a hauling vehicle, self-contained power-operated mechanism connected to said roller to rotate the same while filled with liquid and while engaging the road surface, and mechanism between said frames for lifting the roller up off the road when empty and while the front end of said vehicle frame is hitched to and supported by a hauling vehicle and the rear end of said vehicle is supported by said wheels.

7. In a road roller, the combination with a vehicle frame, of steering mechanism comprising supporting wheels connected to the rear end of said vehicle frame so as to remain at all times in engagement with the ground, a supplemental frame pivoted at its rear end to said vehicle frame intermediate the ends of the latter, a road roller mounted on said supplemental frame, a fluid pressure motor pivotally connected at its ends to said frames at the forward ends of the latter, a fluid pressure pump connected to said motor, and connections comprising valve mechanism between said pump and motor for effecting positive adjustment in elevation of the front end of the supplemental frame when the front end of the vehicle frame is supported independently of said roller and for effecting positive adjustment in elevation of the front end of said vehicle frame when the front end of said supplemental frame is supported by the roller resting on the ground.

8. In a road roller, the combination with a main frame, of a wheeled support for the rear end thereof, a hitching device adapted to connect the front end of said main frame to a hauling vehicle, a sub-frame pivoted to said main frame on a transverse horizontal axis and intermediate the ends of the latter, a road roller mounted on said sub-frame, and locking mechanism between said frames for holding the axis of the road roller in predetermined relation to said frames.

9. In a road roller, the combination with a supporting frame, of a wheeled support for one end thereof, a hitching device at the other end of said frame and adapted for connection to a transporting vehicle, a road roller, and a supplemental frame connecting said roller to said supporting frame to give freedom of movement up and down of the roller relatively to said supporting frame intermediate the ends thereof so that the entire weight of the roller will be supported on the roadway while the machine is being transported therealong by said vehicle.

10. In a trailer road roller, the combination with a supporting frame, of a wheeled support for the rear end thereof, a hitching device at the front end thereof adapted to be connected to a hauling vehicle, a road roller, a supplemental frame connected to said vehicle for movement therewith along the roadway and for movement

up and down relatively to said supporting frame intermediate the ends of the latter to secure support of said roller on the roadway independently of said rear wheeled support and said front hitching device, whereby the weight on the wheeled support is independent of the weight of the roller.

11. In a trailer road roller, the combination with a main frame, of a wheeled support for the rear end thereof, a hitching device for supporting the forward end of said frame on the rear end of a hauling vehicle, a supplemental frame pivoted to said main frame on a transverse axis between said hitching device and said rear wheeled support, and a road roller mounted on said supplemental frame to rotate relatively thereto on a transverse axis parallel to said first-named axis and spaced therefrom, whereby the weight of the roller on the roadway will be independent of the weight on the wheeled support.

12. In a road roller, the combination with a frame, of a road engaging roller mounted thereon and supporting one end thereof, power means for driving said roller, a transversely extending axle pivoted to said frame on a longitudinal horizontal axis, wheels at the ends of said axle, and steering means for said wheels, said axle and wheels supporting the other end of said frame while providing relative tilting between said axle and frame on said longitudinal horizontal axis, to permit one of said wheels to travel along an elevated surface at one side of the path of travel of the roller.

13. In a self-contained power-operated roller, the combination with a roller unit comprising a supporting frame having mounted thereon self-contained power-operated apparatus connected to a ground engaging roller to drive the same, of a hauling and steering frame, steering mechanism at the rear end of said hauling and steering frame, a pivotal connection between said roller unit and said hauling and steering frame intermediate the ends of the latter, mechanism at the front end of said hauling and steering frame adapted to be connected to a hauling vehicle, mechanism between said frames at the forward end of the roller unit to adjust the elevation of the roller relative to the hauling and steering frame, an operator's station at the rear end of the machine, and controls within reach of the operator at said station for effecting operation of the roller and steering of the machine.

14. In a road rolling machine, the combination with a main frame, of a sub-frame pivoted thereto on a transverse axis, steering means connected to the rear end of said main frame, a roller on said sub-frame, power-operated apparatus for driving said roller to propel the machine, mechanism adapted to connect said main frame to a towing vehicle, and means for adjusting the relative positions of said frames including the elevation of the roller off the roadway when said mechanism is connected to said towing vehicle for support of the front end of the main frame thereby while the rear end of said frame is supported by said steering means.

15. In a trailer road roller, the combination with a main frame, of steering mechanism connected to the rear end thereof, a sub-frame, a roller carried by said sub-frame, a device adapted to hitch the front end of the main frame to a towing vehicle frame, and mechanism for adjusting the relative positions of said frames on a horizontal transverse axis to regulate the downward pressure on the roadway exerted by said roller as it travels along behind the towing vehicle.

16. In a road roller, the combination with a vehicle frame, of steering wheels for supporting the rear end of said frame, mechanism at the front end of said frame to connect the same to a fast traveling hauling vehicle for rapid transportation, a supplemental frame connected to said vehicle frame for adjustment relative thereto, a roller mounted on said supplemental frame, self-contained power-operated apparatus connected to said roller to drive the same and thereby propel the machine for rolling purposes while said wheels remain in engagement with the surface being rolled and while the vehicle frame is disconnected from said hauling vehicle, steering mechanism connected to said wheels, and means between said frames for adjusting the elevation of the front end of said vehicle frame relative to the hauling vehicle and for adjusting the elevation of the roller relative to the road surface when said vehicle frame is connected to said hauling vehicle, the construction and arrangement being such that when the roller engages said surface, the front end of the vehicle frame may be adjusted in elevation for connection to the hauling vehicle and when the front end of the vehicle frame has been connected to the hauling vehicle the roller may be lifted off the road surface to facilitate the aforesaid rapid transportation.

17. In a road roller, the combination with supporting framework, of rear steering wheels for supporting the rear end of said framework, a roller mounted in said framework remote from said steering wheels in position to support the forward portion of the framework while said steering wheels support the rear portion thereof, means remote from said steering wheels comprising a fluid pressure motor for adjusting the elevation of said roller relative to said framework, and means comprising a pump connected to said fluid pressure motor to operate the same.

18. A road roller comprising supporting framework and a roller mounted therein, steering mechanism mounted on said framework independently of said roller, means comprising a fluid pressure motor distant from said steering mechanism for adjusting the elevation of said roller relative to said framework, a double acting pump connected to said motor, and valve mechanism for controlling the direction of movement of the motor to effect adjustment in elevation relative to the road surface of that end of the framework adjacent the roller.

19. In a road rolling machine, the combination with a main frame, of a pair of supporting and steering wheels at the rear end thereof, steering mechanism connected to said steering wheels, a supplemental frame connected to said main frame for tilting adjustment relative thereto, a roller mounted on said supplemental frame at the forward end portion of the machine, an operator's station at the rear end of the machine, self-contained power-operated mechanism for driving said roller to propel the machine under the control of the operator at said station, said steering mechanism being also operable from said station, and means for adjusting the relative tilting of said frames to maintain the supplemental frame approximately horizontal on grades.

20. In a road rolling machine, the combination with a main frame, of supporting wheels for one end of said frame, steering mechanism connected to said wheels, a supplemental frame connected to said main frame for tilting adjustment relative thereto, a road roller connected to said supplemental frame, self-contained power-operated ap-

paratus connected to said roller to drive the same and thereby propel the machine along the roadway, and mechanism for adjusting the tilting of said frames relative to each other and each relative to the level of the road surface.

21. In a trailer road roller, the combination with a supporting frame, of steering apparatus connected to the rear end thereof, mechanism for hitching the front end of said frame to a towing vehicle for support thereby against upward and downward movements relative to said towing vehicle, a road roller, means for connecting said road roller to said frame for adjustment in elevation relative thereto, and means for adjusting the elevation of said road roller relative to said frame to regulate the downward pressure on the roadway exerted by the roller as it travels along behind the towing vehicle and said hitching mechanism holds down the front end of the frame while said steering apparatus is being operated to co-act with the towing vehicle in keeping the roller traveling along its working path.

22. In a road roller, the combination with a vehicle frame, of supporting wheels for the rear end thereof, a sub-frame pivoted at its rear end to said vehicle frame intermediate the ends of the latter, a road roller mounted on said sub-frame, a receptacle for water mounted on said sub-frame, self-contained power-operated mechanism connected directly to said road roller to drive the latter and thereby propel the machine along a roadway, means between said frames for adjusting the relative positions thereof and thereby adjust the tilting of said water receptacle relative to the road surface, means comprising a valve for flowing water from said receptacle on to said roller, means for controlling said self-contained power-operated mechanism from a single operator's station, and means for operating said valve from said station.

23. In a road rolling machine, the combination with a supporting frame, of supporting steering wheels for the rear end of said frame, steering mechanism connected to said wheels, a hitching device at the other end of said frame and adapted for supporting connection to a self-propelled truck, a road roller, and means for connecting said road roller to said frame between said hitching device and said steering wheels for freedom of up and down movement relatively to said frame so that the entire weight of the roller will be supported on the roadway while the machine is being transported therealong by said self-propelled truck.

24. In a portable road rolling machine, the combination with a vehicle frame, of a roller connected thereto, steering apparatus connected to said frame, an engine, power transmission mechanism between said engine and said roller, means comprising a clutch and reversing mechanism for connecting the engine to said power transmission mechanism to drive the roller in either direction to secure rolling back and forth over a patch in the roadway, an operating lever, mechanism connected between said lever and said clutch to effect the application of the latter whether the lever is moved in one direction or the other, and means for effecting the setting of the reversing mechanism for driving the roller in opposite directions when said lever is driven in opposite directions, the construction and arrangement being such that when said lever is in neutral position intermediate its limits said clutch is in released position.

25. In a road rolling machine, the combination with a vehicle frame, of a road roller connected

thereto, steering apparatus connected to said frame, an engine mounted on said frame, power transmission mechanism connected to said roller and comprising a reversing gearing, a manual lever mounted to be moved forwardly and rearwardly longitudinally of the machine, a clutch between the engine and the power transmission mechanism, mechanism comprising a rock shaft between said lever and said clutch for effecting the application of the latter whether the lever is moved forwardly or rearwardly from its intermediate neutral position, and mechanism comprising a Y-actuator connected between said rock shaft and said reversing gearing to enable the swinging of said lever forwardly to effect operation of the machine in one direction and the swinging of the lever in the opposite direction to effect reverse operation of the machine.

26. In a road roller, the combination with supporting framework, of a hitching device adapted to pivotally connect said frame-work to a hauling vehicle for lateral swinging movement relatively to the latter on the upright axis of said pivot, steering apparatus at the rear end of said frame-

work, a road roller adjustably supported on said framework, and non-road engaging means for moving the roller up off the roadway when the framework is hitched to said hauling vehicle and derives its sole support from the hauling vehicle and said steering apparatus, the construction and arrangement being such that when the roller engages the roadway it is operated by the hauling vehicle and controlled in its swinging movements on said pivot by said steering mechanism.

27. In a road roller, the combination with rectangular open main frame, of a rectangular sub-frame pivoted to said main frame to occupy positions within the same, a roller connected to said sub-frame, self-contained power-operated mechanism for driving said roller to propel the machine along the roadway, steering wheels for supporting one end of said main frame, steering mechanism connected to said wheels, and fluid-pressure motor mechanism between said frames for tilting the sub-frame relatively to the main frame on the pivotal connection between the same.

RAYMOND W. KEELER.
